UNITED STATES PATENT OFFICE.

DANIEL A. DORAN, OF YONKERS, NEW YORK.

MAIL ELEVATOR.

Application filed December 9, 1922. Serial No. 605,788.

To all whom it may concern:

Be it known that I, DANIEL A. DORAN, a citizen of the United States, and residing at Yonkers, in the county of Westchester and State of New York, have invented certain new and useful Improvements in Mail Elevators, of which the following is a specification, such as will enable those skilled in the art to which it appertains to make and use the same.

This invention relates to mail elevators or lifts and particularly to apparatus of this class designed for use in raising and lowering mail in an apartment house or other building or dwelling and the object of the invention is to provide an apparatus of the class specified, by means of which mail or the like may be automatically raised from a predetermined point in a building to different apartments and floors of a building; a further object being to provide an apparatus of the class specified, which is automatic in operation and the operation of which is controlled by the opening and closing of the doors selected to predetermined apartments of a building; a further object being to provide means for taking up the slack of the ropes or cables for operating the mail boxes of the apparatus, and with these and other objects in view, the invention consists in an apparatus of the class and for the purpose specified, which is simple in construction, efficient in use, and which is constructed as hereinafter described and claimed.

The invention is fully disclosed in the following specification of which the accompanying drawing forms a part, in which the separate parts of my improvement are designated by suitable reference characters in each of the views, and in which:

Fig. 1 is a diagrammatic view showing one method of carrying my invention into effect with parts of the construction broken away in section.

Fig. 2 is a partial section on the line 2—2 of Fig. 1 and on an enlarged scale.

Fig. 3 is a diagrammatic view of the electric circuit of one complete unit of my apparatus.

Fig. 4 is a partial section on the line 4—4 of Fig. 2 and on an enlarged scale; and,

Figs. 5 and 6 are detail sectional views of parts of the automatic circuit maker and breaker which I employ.

In the drawing I have indicated for the

purpose of illustrating the method of carrying my invention into effect, three mail elevator shafts 10, the lower ends of which lead to a predetermined point in a building, 60 preferably the vestibule or entrance room of a building and at 11 I have shown a part of the wall of such room with a large door 12 movably mounted therein and normally closed by a suitable lock 13 and to the door 12 are hinged other doors 14 controlled by suitable locks 15 which control the admission to the lower ends of the separate shaft 10 employed, and the doors 12 are preferably provided with transparent panels 16. 70 The shafts 10 terminate at the door opening controlled by the door 12 and are provided with apertures 17 to permit of the insertion and removal of mail whenever desired and the shafts 10 extend upwardly into the 75 building to predetermined apartments and to rooms in said apartments or to predetermined points on the separate floors of a building, and are provided at the upper ends thereof with door openings 18 controlled by 80 hinged doors 19.

Mounted in the separate shafts 10, only one of which is shown in detail in the drawing, are mail receiving and carrying members 20 of the construction shown in Figs. 85 2 and 4 of the drawing and comprising a bottom plate 21 an arc-shaped back plate 22 and comparatively straight side walls or plates 23 and mounted in connection with the bottom plate 21 is an upwardly, inwardly and outwardly directed spring member 24 adapted to retain letters or the like placed in the members 20 against displacement, and extending longitudinally of the corner portions of the member 20 are rods 25 which 95 are contracted at the top and bottom of the member 20 and provided with loops or eyes with which a cord or cable 26 is connected, and annular trip members 27 are mounted in connection with the loops or eyes of said 100 rods. The rods 25 are bowed outwardly from the member 20 or the corner portion thereof and are adapted to guide the member 20 in its passage through the shaft 10 and are also free of expansion and contraction by reason of the spring properties thereof.

The cord or cable 26 passes from the top of the member 20 upwardly around a pulley 28 at the top of the shaft and then downwardly through the shaft and around a drum 29 and then upwardly to the bottom

of the member 20 and said cord or cable is wound once around the drum 29 to insure the movement of said cable by said drum.

The drum 29 is located at a predetermined distance below the door 12 which controls the admission to the lower ends of the shafts 10 and is mounted upon a shaft 30 supported upon a table 31 by suitable bearings, said table 31 being provided with a downwardly directed extension 32 movable in and guided by a supporting sleeve 33, and the lower end of the extension 32 operates upon a spring 34 mounted in the sleeve 33.

Supported upon the table 31 is a small electric motor 35 upon the shaft of which is a worm 36 adapted to cooperate with a worm gear 37 on the shaft 30 of the drum 29 and by means of which said drum is rotated to move the mail receiving and carrying member 20 upwardly and downwardly in the shaft 10.

Connected with the motor 35 are three circuit wires 38, 39 and 40 and the circuit wire 38 extends upwardly to the top portion of the shaft 10 and the circuit therethrough is controlled by a switch device 41 while the wire 39 extends upwardly to the lower end of the shaft 10, and the circuit therethrough is controlled by a switch device 42 and the wire 38 through the switch device 41 extends to a contact 43 while the wire 39 through the switch 42 extends to a contact 44 and the contacts 43 and 44 are located in juxtaposition to the door 19 and the circuits therethrough are controlled by a switch arm 45 mounted in connection with the door 19 and movable into and out of contact with the separate contacts 43 and 44 respectively.

The wire 40 is connected with a suitable source of electrical supply indicated at 46 in Figs. 2 and 3 of the drawing, and the circuit through the wire 40 is controlled by a switch 47 mounted in connection with and actuated by the lock 13 of the door 12, whereby when the door 12 is opened, the entire circuit is broken to prevent the operation of the mail holder and carrier 20 as will be apparent.

The operation of my improved mail elevator will be readily understood from the foregoing description when taken in connection with the accompanying drawings and the following statement. It will be understood that I have shown but one of the shafts 50 of an apparatus, and have indicated part of three shafts, but in practice any number of these shafts may be employed, it being understood that the structure of each shaft will be the same as the one shaft shown in Figs. 1 and 2 of the drawing, each shaft being provided with independent motor support, electric motor and drum, and by reason of the form of the member 20 or the separate members 20 in the shafts employed, a greater number of these shafts and members

20 may occupy a predetermined space, and the mail placed in the member 20 or members 20 is supported in arc-shaped fashion as indicated at 48 in Fig. 4 of the drawing. Normally the member 20 is at the bottom of the shaft 10 as illustrated in Fig. 2 of the drawing, and the doors 12 and 19 are closed and the switches 41, 42 and 45 are in the position shown in Fig. 3 of the drawing. If a letter carrier now opens the door 12 as shown in Fig. 2 of the drawing to insert mail in the member 20 of one shaft 10 or said members of a number of shafts, the circuit will be broken through the wires 38, 39 and 40 and the opening of the door 19 of one shaft will not cause the member 20 to be raised. In closing the door 12 and moving the lock 13 and the switch 47 thereof into operative position, the circuit is closed through the wire 40, and if a tenant or other party should open the door 19 leading to the shaft 10, the switch 45 will be moved from the position shown in Fig. 3 and Fig. 6 of the drawing, in which position it is in circuit with the contact 44, into the position shown in Fig. 5 in which it is in circuit with the contact 43. This operation will complete the circuit to the motor 35 and will cause the member 20 to be raised in the shaft 10 until the trip 27 at the top of the member 20 strikes the switch 41 to move the same into position to break the circuit through the wire 38 and automatically stop the motor 35.

In the above described operation, the switch 42 is automatically moved into position to close the circuit through the wire 39 by a spring 42^a employed for this purpose and after the mail has been removed from the member 20 through the door opening 18 by the tenant or other party, and the door 19 is again closed, the circuit is again completed to the motor 35 through the contact 44 and switch 42, and the motor is rotated in an opposite direction by reason of the wiring employed, and the member 20 is moved downwardly in the shaft 10, and when the trip 27 at the bottom of the member 20 strikes the switch 42, said switch is moved into inoperative position and the circuit is again broken to the motor 35 and the member 20 automatically stopped. In the last named operation, it will also be understood that the switch 41 is returned to its normal or operative position by a spring 41^a and the various parts of the apparatus are again in the first named position, and the above operation may be repeated as often as desired, it being understood that as long as the door 12 is in a closed position, the member 20 may be automatically raised and lowered in the shaft 10 by the opening and closing of the door 19.

It will also be understood that the shafts 10 may extend in a straight, upright position in a building or may be extended at

different angles or to any predetermined point in a building by suitably constructing the shafts.

I also preferably employ in the wall structure 11 beneath the door 12, a compartment 49 adapted to receive mail that cannot be placed in the members 20, and this compartment is controlled by a door 50, but my invention is not necessarily limited to the 10 use of the compartment 49 nor to other details of construction herein described and various changes therein and modifications thereof may be made within the scope of the appended claims without departing from 15 the spirit of my invention or sacrificing its advantages.

Having fully described my invention, what I claim as new and desire to secure by Letters Patent, is:—

20 1. An apparatus of the class described, comprising a shaft, a mail receiving and carrying member mounted in said shaft and movable therethrough from one end portion thereof to the other, the end portions of said shaft being provided with openings, doors 25 for closing said openings, means involving an electric motor for moving said member in both directions from one end portion of said shaft to the other and in juxtaposition to said openings, said motor being in an electric circuit, means at the end portions of said shaft adapted to be actuated by trip devices connected with said member for controlling the circuit to said motor, and the 30 for governing the direction of the movement of said member in said shaft, a switch device actuated by one of said doors cooperating with said last named means for controlling the circuit through said motor, and the other of said doors being provided with a switch device for making and breaking the circuit to said motor.

2. An apparatus of the class described, comprising a shaft, a mail receiving and carrying member mounted in said shaft and movable therethrough from one end portion thereof to the other, the end portions of said shaft being provided with openings, doors for closing said openings, means involving an electric motor for moving said member from one end portion of said shaft to the other and in juxtaposition to said openings, said motor being in an electric circuit, means at the end portions of said shaft 45 adapted to be actuated by trip devices connected with said member for controlling the circuit to said motor, and for governing the direction of the movement of said member in said shaft, a switch device actuated by one of said doors cooperating with said last named means for controlling the circuit through said motor, and the other of said doors being provided with a switch device for making and breaking the circuit to said 50 motor, and said motor and operating means

being mounted on a movable support to take up the slack in the cable for supporting and moving said member in said shaft.

3. In an apparatus of the class described, a shaft, a member mounted in and movable 70 through said shaft from one end thereof to the other, an endless cable to which said member is secured and by means of which the same is operated, said cable passing over a pulley at the upper end of the shaft, 75 means involving an electric motor at the lower end of the shaft for operating said cable and said member to positively drive said member upwardly and downwardly through the shaft, said last named means 80 being mounted on a movable support, whereby the weight thereof will take up the slack in said cable, tensional means for partially supporting said movable support, said member being provided with resilient guide members 85 to permit of its free passage through said shaft, the body portion of said member being arc-shaped in form, tensional means for securely holding mail in connection therewith, said motor being in an electric 90 circuit, and means automatically actuated by said member for controlling the circuit to said motor.

4. In an apparatus of the class described, a shaft, a member mounted in and movable 95 through said shaft from one end thereof to the other, an endless cable to which said member is secured and by means of which the same is operated, said cable passing over a pulley at the upper end of the shaft, means involving an electric motor at the lower end of the shaft for operating said cable and said member to positively drive said member upwardly and downwardly through the shaft, said last named means 100 being mounted on a movable support, whereby the weight thereof will take up the slack in said cable, tensional means for partially supporting said movable support, said member being provided with resilient guide members 105 to permit of its free passage through said shaft, the body portions of said member being arc-shaped in form, tensional means for securely holding mail in connection therewith, said motor being in an electric circuit, means automatically actuated by said member 110 for controlling the circuit to said motor, and other means for controlling the circuit to said motor.

5. In an apparatus of the class described, a shaft, a member mounted in and movable through said shaft from one end thereof to the other, an endless cable to which said member is secured and by means of which the same is operated, said cable passing over a pulley at the upper end of the shaft, means involving an electric motor at the lower end of the shaft for operating said cable and said member to positively drive said member upwardly and downwardly through the 115 120 125 130

shaft, said last named means being mounted on a movable support, whereby the weight thereof will take up the slack in said cable, tensional means for partially supporting 5 said movable support, said member being provided with resilient guide members to permit of its free passage through said shaft, the body portion of said member being arc-shaped in form, tensional means for 10 securely holding mail in connection therewith, said motor being in an electric circuit, means automatically actuated by said member for controlling the circuit to said motor, other means for controlling the circuit to 15 said motor, and means independent of said last named means for opening and closing the motor circuit.

6. A mail elevator apparatus of the class described comprising a plurality of shafts, 20 the lower ends of said shafts being located at a predetermined point in a building, and the upper ends thereof extending to predetermined floors and apartments of a building, the lower ends of said shafts being provided with openings to give access thereto, 25 a door for closing all of said openings, and the upper ends of the shafts being provided with openings closed by independent doors, mail receiving and carrying members mounted 30 in said shafts and movable from one end portion thereof to the other, the body portions of said members being arc-shaped in form, tensional means for retaining mail 35 therein, said members being provided with resilient guide members and means involving electric motors mounted below the lower ends of said shafts for moving said members upwardly and downwardly through said shafts.

40 7. A mail elevator apparatus of the class described comprising a plurality of shafts, the lower ends of said shafts being located at a predetermined point in a building, and the upper ends thereof extending to predetermined floors and apartments of a building, the lower ends of said shafts being provided with openings to give access thereto, 45 a door for closing all of said openings, and the upper ends of the shafts being provided with openings closed by independent doors, mail receiving and carrying members mounted in said shafts and movable from one end portion thereof to the other, the body portions of said members being arc-shaped in form, tensional means for retaining mail 50 therein, said members being provided with resilient guide members, means involving electric motors mounted below the lower ends of said shafts for moving said members upwardly and downwardly through said shafts, said means involving cables driven by said motors, and said means being movably supported and suspended by said cables to take up the slack therein in the operation of said members in said shafts, 55 said cables to be movable supported and suspended by said cables to take up the slack therein in the operation of said members in said shafts, the operation of said members in said shafts.

8. A mail elevator apparatus of the class described comprising a plurality of shafts, the lower ends of said shafts being located at a predetermined point in a building, and the upper ends thereof extending to predetermined floors and apartments of a building, the lower ends of said shafts being provided with openings to give access thereto, a door for closing all of said openings, and the upper ends of the shafts being provided with openings closed by independent doors, mail receiving and carrying members mounted in said shafts and movable from one end portion thereof to the other, the body portions of said members being arc-shaped in 70 form, tensional means for retaining mail therein, said members being provided with resilient guide members, means involving electric motors mounted below the lower ends of said shafts for moving said members upwardly and downwardly through said shafts, said means involving cables driven by said motors, said means being movably supported and suspended by said cables to take up the slack therein in the operation of 75 said members in said shafts, said electric motors being in electric circuits, and automatically operated means at the upper and lower ends of the separate shafts for controlling the circuits to said motors.

9. A mail elevator apparatus of the class described comprising a plurality of shafts, the lower ends of said shafts being located at a predetermined point in a building, and the upper ends thereof extending to predetermined floors and apartments of a building, the lower ends of said shafts being provided with openings to give access thereto, a door for closing all of said openings, and the upper ends of the shafts being provided with openings closed by independent doors, mail receiving and carrying members mounted in said shafts and movable from one end portion thereof to the other, the body portions of said members being arc-shaped in form, tensional means for retaining mail therein, said members being provided with resilient guide members, means involving electric motors mounted below the lower ends of said shafts for moving said members upwardly and downwardly through said shafts, said means involving cables driven by said motors, said means being movably supported and suspended by said cables to take up the slack therein in the operation of said members in said shafts, said electric motors being in electric circuits, automatically operated means at the upper and lower ends of the separate shafts for controlling the circuits to said motors, and other means at the upper end portions of said shafts for controlling the circuits to said motor.

10. A mail elevator apparatus of the class described comprising a plurality of shafts,

- the lower ends of said shafts being located at a predetermined point in a building, and the upper ends thereof extending to predetermined floors and apartments of a building, the lower ends of said shafts being provided with openings to give access thereto, a door for closing all of said openings, and the upper ends of the shafts being provided with openings closed by independent doors, 5 mail receiving and carrying members mounted in said shafts and movable from one end portion thereof to the other, the body portions of said members being arc-shaped in form, tensional means for retaining mail 10 therein, said members being provided with resilient guide members, means involving electric motors mounted below the lower ends of said shafts for moving said members upwardly and downwardly through said 15 shafts, said means involving cables driven by said motors, said means being movably supported and suspended by said cables to take up the slack therein in the operation of said members in said shafts, said electric 20 motors being in electric circuits, automatically operated means at the upper and lower ends of the separate shafts for controlling 25 the circuit to said motors, other means at the upper end portions of said shafts for controlling the circuits to said motor, and means for opening and closing the motor circuits.
11. A mail elevator apparatus of the class described comprising a plurality of independent shafts, mail receiving and carrying members mounted in said shafts and movable from one end portion thereof to the other, means in each of said shafts and including an electric motor for moving said members upwardly and downwardly 40 through the shaft, means involving electric motors at one end portion of each of said shafts and an endless conveyor driven by said motor for positively moving said members upwardly and downwardly through 45 said shafts, and said means being movably supported and suspended by said conveyors to take up the slack therein in the operation of said members in said shafts.

In testimony that I claim the foregoing as my invention I have signed my name this 29th day of November 1922.

DANIEL A. DORAN.
